UNITED STATES PATENT OFFICE.

CARLOS A. SMITH, SR., OF BELLAIRE, OHIO.

RUG AND CARPET SCRUBBING APPARATUS.

Application filed November 29, 1926. Serial No. 151,349.

This invention relates broadly to laundering apparatus, and more specifically to a machine for scrubbing rugs, carpets and the like.

5 The primary object of the invention is to provide a carpet and rug cleansing mechanism designed for the use of public laundries and cleaning establishments and which is not limited to use on carpets and rugs of the 10 usual commercial sizes, but is applicable with equal facility to carpets and rugs of substantially all sizes.

A further object is to provide a machine of the character mentioned which is shiftable over the floor and which, therefore, is adapted for movement relative to rugs or carpets spread upon the floor while such rugs or carpets remain stationary.

With these and other important objects in view, the invention resides in the features of construction, arrangement of parts and combinations of elements which will hereinafter be fully described, reference being had to the accompanying drawings, in which—

25 Figure 1 is a top plan view of the invention;

Figure 2 is a front end elevation of the same;

30 Figure 3 is a sectional elevation, the section being taken on line 3—3, Fig. 1;

Figure 4 is an enlarged detail section on line 4—4, Fig. 3;

Figure 5 is a section on line 5—5, Fig. 2;

35 Figure 6 is a partial section on line 6—6, Fig. 3;

Figure 7 is an enlarged longitudinal section of the spray pipe for the cleansing solution;

Figure 8 is a section of the same on line 40 8—8, Fig. 7;

Figure 9 is a longitudinal section of the water-spray pipe;

Figure 10 is an enlarged detail section on line 10—10, Fig. 3;

45 Figure 11 is a broken section on line 11—11, Fig. 1;

Figure 12 is an enlarged horizontal section of one of the suction nozzles taken on line 12—12, Fig. 11; and—

50 Figure 13 is an enlarged end elevation of the carder roll or brush.

Referring to said drawings, 1 designates the front end, 2 the rear end, and 3 and 4 the opposite sides of a rectangular frame 55 which is preferably formed of lengths of

angle-iron. Rigidly carried by the sides 3 and 4 in oppositely disposed relation adjacent to the ends of said sides are pairs of brackets 5 and 6 in which are journaled transverse shafts 7. Fixed upon said shafts 60 between each set of brackets 5 and 6 is a cog wheel 8 and one or more carriage wheels 9, the latter being designed for travel upon vertically disposed tread members 10^a formed on each of a pair of parallel track rails 10 laid upon the floor 11, and upon which the machine is designed to travel back and forth for operating upon floor coverings spread upon the floor between said rails. Said rails have formed thereon, preferably 70 between the tread members 10^a, a toothed rack 10^b designed to be engaged by the cog wheels 8 for propelling the machine over the trackway.

Supported by the carriage frame, as by 75 brackets 12, is a tank or reservoir 13 for a cleansing solution which feeds by gravity to a suitably located transversely arranged spray pipe 14 which has therein one or more 80 rows of perforations 15 through which said solution is sprayed upon the main cleansing brushes 16, two of the latter disposed in closely associated relation being employed in the embodiment of the invention shown in the drawings. Said brushes 16 are of cylindrical type and are designed to be rapidly rotated in close bearing relation to the underlying carpet for applying to the latter the cleansing solution and for exerting upon the carpet a vigorous rotary scrubbing action. Each of said brushes is journaled upon an auxiliary frame which is vertically shiftable so that said brushes may be elevated out of contact with the carpet when occasion requires, as will hereinafter be explained. 85

The auxiliary frame mentioned comprises opposite end members which are generally designated by the reference numeral 17. The trunnions 16^a of said brushes project through vertical guide slots 18 provided 100 therefor in the sides 3 and 4 of the main frame, or in depending arm-like portions 3^a of said frame, and are journaled in said end members 17 of the auxiliary frame, as is most clearly shown in Fig. 5. Also journaled in said end members 17, or in depending arms 17^a provided at opposite ends of the latter, are trunnions 19^a of cylindrical rolls 19, preferably of the type commonly termed "carder rolls", which are equipped 110

peripherally with carpet-entering pins, as shown in Fig. 13, and which travel upon the carpet forward and rearward of the cleansing brushes 16 and which are designed to travel upon the carpet and to prevent lifting of the latter under the action of said brushes. Said trunnions 19^a are projected through vertical slots 20 provided therefor in depending arms 21 carried by the sides 3 and 4 of the carriage frame. For the purpose of normally maintaining said rolls 19 in yielding pressure exerting relation to the carpet, compression springs 22 are interposed vertically between blocks 23 which ride upon said trunnions 19^a and an overhanging fixed member, as the plate 24^a which is rigidly mounted between the side and a thereto-attached slotted bracket 24, as shown in Fig. 10.

The end members 17 of the auxiliary frame rest midway between their ends upon cams 25 which are fixed upon a transverse shaft 26 which is journaled in bearings 27 borne by the sides 3 and 4 of the main frame. A hand lever 28 fixed upon said shaft 26 is shiftable to and from the full line position thereof shown in Figs. 3 and 5 to lower and elevate the scrubbing brushes 16 and the carder rolls relative to their operative positions on the underlying carpet, such movements of said lever producing rotation of the cams 25 for elevating and lowering the auxiliary frame. Obviously, such movements of the auxiliary frame relative to the main frame are permitted by reason of the provision of the guide slots 18 and 20 hereinbefore referred to.

Each of the trunnions 16^a of the brushes at one side of the main frame carries a gear wheel 80 disposed in driven relation to a similar gear 29 carried by a shaft 30 which is suitably journaled in the end members 17 of the auxiliary frame, and said shafts 30 are suitably driven, as by belts 31 and 32, from the rotor shaft 33 of an electric motor 34 which is appropriately mounted, as upon a laterally disposed table or apron 35 borne by the main frame of the carriage. Said drive belts 31 and 32 are preferably arranged to effect rotation of the brushes 16 in opposite directions, as indicated by arrows in Fig. 3, the belt 31 connecting pulleys 36 and 37 carried, respectively, by the rotor shaft 33 and the adjacent end of one of the shafts 30, and the belt 32 connecting pulleys 38 and 39 carried, respectively, by the last mentioned shaft and the opposite shaft 30, all as shown in Fig. 1.

For propelling the carriage forward along the trackway, power is communicated to the rearmost of the cog-bearing shafts 7 by suitable transmission means, that herein shown for illustrative purposes comprising a belt 40 which connects pulleys 41 and 42 carried,

respectively, by the rotor shaft 33 and a suitably located countershaft 43 journaled upon the apron 35. From said shaft the power is communicated to a shaft 44 through a suitable train of reduction gearing designated generally by the numeral 45; and said shaft 44 in turn communicates the power to the rearmost of the shafts 7 through the intermediary of a shaft 44^a which is inclined downward to the latter and which has universal-joint connection at its opposite ends with the driving shaft 44 and the driven shaft 7, as shown.

The pulley 42 has its hub 42^a rotatable on the countershaft 43, and provided on the outer face of said hub are forwardly inclined ratchet teeth which, in the forward rotation of said pulley, operatively engage similar teeth on the opposing face of a collar 72 which is fixed to said countershaft. A second pulley 73 is rotatably mounted on the countershaft 43 and is connected by a belt 74 to a pulley 75 fixed on the rotor shaft 33. The hub of said pulley 73 carries on its inner face ratchet teeth which are rearwardly inclined and which, in rearward rotation of said pulley, operatively engage similar teeth formed on the opposing face of a collar 77 which is fixed on the countershaft. Said pulleys 42 and 73 are yieldingly held in engagement with the collars 72 and 77, respectively, by an interposed compression spring 78. It will be understood that when it is desired to propel the carriage forward, the rotor shaft is driven in a direction for driving the countershaft forward through the pulley 42 and when the carriage is to be reversed, the rotor shaft is reversed for driving said shaft rearward through the pulley 73. It will also be understood that the inclined teeth of the hub of pulley 73 ride freely over the teeth of the collar 77 when the countershaft is being rotated forward, and that the teeth of the hub of pulley 42 ride over the teeth of the collar 72 when the countershaft is being driven rearward.

The rearmost of the carder rolls 19 is herein shown as driven by a sprocket chain 46 connecting sprocket wheels 47 and 48 carried, respectively, by the said shaft 7 and a trunnion 19^a of said carder roll 19, and the foremost of the carder rolls is driven by a sprocket chain 49 connecting sprocket wheels 50 and 51 carried, respectively, by the foremost shaft 7 and the trunnion of said carder roll.

Mounted upon the main frame of the carriage rearward of the scrubbing rolls is a perforated spray pipe 52 by means of which water is sprayed upon the carpet to effect dilution of the soap solution which remains following the passage of the scrubbing brushes and also to assist in dissolving and loosening foreign matter which has not been removed by said brushes. Water may be

supplied to said pipe 52 through a flexible hose (not shown) from any suitable source of supply.

A scraper blade 53 preferably is carried by the main frame at a suitable point rearward of the scrubbing brushes, the same being vertically shiftable into and out of operative relation to the carpet acted upon. Said blade is movable in guideways provided in suitable guide members 54 carried by the main frame.

Located rearward of the scraper blade 53 is suction means whereby water and foreign matter carried by the carpet may be taken up and conducted away, said means comprising a plurality of complementally arranged suction nozzles 55 which have communication through thereto attached flexible tubes 56 with a transversely disposed pipe 57 which is designed to be connected, as by means of a flexible tube (not shown) to a suitable source of suction, as an air pump or vacuum device (not shown). As herein shown, each suction nozzle 55 is of flattened oblong form and has its mouth partially closed for preventing the lifting of the carpet, the closing means consisting of a bottom end plate 55^a provided with numerous perforations 55^b. Said nozzles are carried by a vertically shiftable member, as a slide plate 58, bolts 59 being employed as the means of attachment. Said bolts are preferably directed through horizontal slots 60 provided therefor in said plate 58 and in which they are shiftable for adjusting the relative positions of the nozzles.

The scraper blade 53 and the slide plate 58 are supported by cams 61 and 62, respectively, which are fixed upon shafts 63 and 64 journaled on the carriage frame. Hand levers 65 and 66 fixed on said shafts 63 and 64, respectively, are provided whereby the cams may be rotated forward and back for elevating and lowering said scraper blade and said slide plate, respectively.

Each of the spray pipes 14 and 52 is provided with adjustable means whereby a portion of the length thereof may be rendered ineffective for spraying purposes, so that the spray from such pipes may be delivered only within a range required by carpets of less than the maximum width for which the mechanism is designed to operate. The means for closing off portions of said pipes 14 and 52 comprises close-fitting pistons 67 and 68, respectively, to which are attached push-and-pull rods or chains, as 69 and 70, which extend thence outward through the open outer ends of said pipes, as shown in Figs. 7 and 9, and which may be operated by hand to effect the required shifting of said pistons.

As herein shown, the scrubbing rolls are geared to be driven at a speed considerably greater than that at which the carriage is

propelled forward; also the gearing is such that the reverse travel of the carriage is at relatively higher speed than the advance travel. As will be understood, in the reverse travel of the carriage, the various levers 28, 65 and 66 are intended to occupy positions wherein the parts with which they are associated are elevated out of operative relation to the underlying floor covering.

It will be understood that numerous changes may be made in the details of construction and arrangement of some of the parts herein shown and described without departing from the spirit or scope of the invention, and, therefore, that I am not to be understood as limiting the invention except as may be required by the express terms of the appended claims.

What is claimed is—

1. The combination with a trackway, of a carriage for traveling upon said trackway, a rotary brush borne by said carriage for acting upon a floor covering disposed between the rails of said trackway, means for lowering and raising said brush, means for supplying a cleansing solution to said brush, positively driven carder rolls for traveling upon the floor covering forward and rearward of said brush, means for propelling said carriage, and means for rotating said brush.

2. The combination with a trackway, of a carriage for traveling upon said trackway, a rotary brush borne by said carriage for acting upon a floor covering disposed between the rails of said trackway, means for vertically moving said brush to and from operative position, means for rotating said brush, means for supplying a cleansing solution to said brush, rotating means for holding the floor covering against longitudinal shifting movement, means for driving said rotating means at the speed of travel of the carriage, and means for propelling said carriage.

3. The combination with a floor-carried trackway, of a carriage for traveling upon said trackway, means for propelling said carriage, a pair of rotary brushes borne by said carriage, means for driving said brushes at speeds exceeding that of the travel of the carriage, means for vertically moving said brushes to and from operative position relative to a stationarily disposed floor covering to be acted upon, means for supplying a cleansing solution to said brushes, rotary means for holding the floor covering against longitudinal movement under the action of said brushes, and means for driving said rotary means at the speed of travel of the carriage.

4. The combination with a floor-carried trackway, of a carriage for traveling upon said trackway, means for propelling said carriage, an auxiliary frame borne by said carriage, means for elevating and lowering

4
said auxiliary frame, rotary brushes journaled on said auxiliary frame, means for driving said brushes, and means for supplying a cleansing solution to said brushes.

5. The combination with a trackway, of a carriage for travel upon said trackway, means for propelling said carriage, rotary brushes journaled on said carriage, rolls located forward and rearward of said 10 brushes whereby a floor covering acted upon by the latter is maintained against shifting movement, means for raising and lowering said brushes and said rolls, means for supplying a cleansing solution to be applied 15 by said brushes, and suction means borne by the carriage whereby foreign matter collected upon said floor covering following the passage of said brushes is removed.

6. The combination with a trackway, of a 20 carriage for travel upon said trackway, means for propelling said carriage, rotary brushes journaled on said carriage, rolls located forward and rearward of said brushes whereby a floor covering acted upon

by the latter is maintained against shifting movement, vertically yieldable means holding said rolls depressed upon said floor covering, manually operated means for elevating and lowering said brushes and said rolls with respect to the floor covering, means for supplying a cleansing solution to be applied by said brushes, and means for removing foreign matter collected upon the floor covering following the action of the 25 30 35 brushes.

7. In combination with a rotary brush for scrubbing floor coverings, and means for actuating said brush, of suction means for removing matter collected upon such covering following the action of said brush, 40 said suction means comprising a plurality of suction nozzles, a vertically shiftable member supporting said nozzles, and means for adjusting the relative positions of said nozzles on said member.

In testimony whereof, I affix my signature.

CARLOS A. SMITH, Sr.
